J. S. McWHIRTER

AIR BRAKE RELEASE

Filed Aug. 4, 1926

Patented Mar. 6, 1928.

1,661,730

UNITED STATES PATENT OFFICE.

JOHN S. McWHIRTER, OF NEW YORK, N. Y.

AIR-BRAKE RELEASE.

Application filed August 4, 1926. Serial No. 126,949.

This invention relates to a novel apparatus for releasing the brakes on vehicles.

More particularly this invention relates to a novel means for causing the release of the 5 brakes on railroad cars, street cars and the like.

One of the objects of this invention is the provision of a novel pneumatic arrangement for releasing the brakes on vehicles after the 10 brake applying mechanism has been deenergized.

A still further object of this invention is the provision of a device of this type which is inter-connected with the fluid pressure 15 source used for applying the brakes so that when the brake applying mechanism is deenergized the brake releasing mechanism is automatically energized.

A further object of this invention is a 20 provision of a novel fluid pressure operated valve for automatically carrying out this operation.

These and many other objects are obtained by means of the construction described 25 herein.

This invention resides substantially in the construction, combination, arrangement and relative location of parts as will be more fully described hereinafter.

Referring to the drawings for which the 30 same reference numerals will be used to indicate the same or similar parts,

Figure 1 is a diagrammatic view of the apparatus employed in my invention;

Fig. 2 is a cross-sectional view of the novel 35 valve comprising one element of this invention; and

Fig. 3 shows a modified device for releasing the brakes.

At the present time it is almost a universal 40 practice in releasing air brakes to equip the brake rigging at some point with releasing springs either coiled or flat with or without suitable adjustment for regulating the amount of pressure to be applied to the 45 brake shoes. It is also common to install within the brake cylinder, a suitable coil spring to aid the movement of the return stroke of the piston to release the brakes.

It has been found in practice that it is almost 50 impossible to adjust the various release springs in such a manner as to apply equal pressure to all the shoes. In the event that unequal pressure is applied, the tendency is for one spring to overcome the tension of

another, thus pulling the shoe on the strong spring away from the wheel and forcing the shoe on the spring toward the wheel resulting in shoe drag. When the brakes are applied, a considerable portion of the energy 60 is used in compressing these springs which lowers the braking efficiency since an excess of the braking power with what is actually needed to brake the train must be provided for. 65

In my invention the springs in the brake cylinder, as well as the other springs applied to the brake shoes are dispensed with and the brakes are released by means of a small air cylinder mounted in such a manner either 70 through levers or by direct connection, to oppose the main brake cylinder and automatically operated through a valve when the brake cylinder is deenergized. 75

Referring to the drawings the fluid pressure source is shown at 1, connected through a pipe 3 to an auxiliary fluid pressure source 2. This source is connected through a pipe 4 to my novel valve 8 which will be described shortly. A small cylinder 5 is connected to 80 this valve by means of the pipe 9, the piston rod 6 is attached to the brake rigging comprising the lever 7 pivoted at 10 and pivotally connected to the piston rod 11 of the brake cylinder 12 in which is mounted for 85 sliding movement the piston 13. This brake cylinder is of the usual construction. Another rod lever 14 is pivoted to the end of the piston rod 11 and is connected by means of the pivoted rod 15 to the pivoted lever 16 90 as shown. The rods 17 and 18 are pivotally connected to the levers 16 and 14 respectively. 95

Another pipe 19 extends from the source 1 to the usual valve 21 through the pipe 20. A return pipe 22 connects the valve with the brake cylinder through the pipe 23. The pipe 22 also extends to the valve 8 through the pipe 24 and continues on to a similar valve 21' to which the pipe 20 also extends. 100

In Fig. 2 is shown the valve construction which comprises a casing 8 in which the piston 40 moves when fluid pressure is supplied thereto against the action of the spring 41. A circumferential groove 42 extends 105 around the piston 40 and when the piston is in its normal or deenergized position, this groove connects the two pipes 4 and 9 together.

The operation of this device is somewhat 110

as follows: When the brakes are applied through operating the valves 21 or 21' which are of the usual construction and are adapted to connect the pipes 22 to the pipe 20 so that fluid pressure is supplied to the cylinder 12. This moves piston 13 to the right and causes the brakes which are attached to the rods 17 and 18 to be applied. At the same time fluid pressure is supplied to the valve 8 to force the piston 40 to the right to move the groove 42 out of register with the pipes 4 and 9 and to permit cylinder 5 to exhaust through pipes 9 and 25. When the valve 21 or 21' is moved to its other position the pipe 22 is open to exhaust so that the cylinder 12 may exhaust therethrough. At the same time piston 40 in the valve 8 moves back to its normal position under the influence of spring 41 since it is open to exhaust also. This places the pipes 4 and 9 in communication and fluid pressure flows from the auxiliary source 2 to the cylinder 5 in which the piston thereof moves to the left to force the lever 7 to the left about its pivot 10. This causes the piston 13 to move over towards the left to its deenergized position. It will be seen therefore that I have supplied a piston means for releasing the brakes which is interconnected with the system for operating the brake cylinder so that the means become automatically active when the brake cylinder is open to exhaust.

I have shown a modification of this arrangement in Fig. 3 where two cylinders 50 are provided which are connected to the pipes 9 from the valve 8. Within these cylinders move the pistons 51 whose rods extend through the walls of cylinder 12 and against the piston 13 as shown in dotted lines at 52. The operation of this apparatus is the same except that the force of the pistons 51 is directly applied to the piston 13 as will be readily apparent in the drawings.

I am well aware that many changes in the details of construction and relative arrangement of the parts will readily suggest themselves to those skilled in the art and I do not therefore desire to be limited to the particular construction disclosed herein but rather to the principles of my invention as it is defined in the appended claims.

What I seek to secure by United States Letters Patent is:

1. In a brake release mechanism the combination with pneumatic air brake applying means including a piston of means interconnected with said brake applying means for releasing the brakes when the brake applying means is deenergized, said interconnect-

ed means being mechanically fastened to the piston of said pneumatic means.

2. In an air brake release mechanism the combination with a brake applying cylinder and a piston of a releasing cylinder and piston energized when said brake applying cylinder is deenergized.

3. In an air brake system the combination with a fluid pressure reservoir, a brake applying means and means for controlling the admission of fluid pressure to said means of means for releasing the brakes when said means is exhausted, said brake releasing means comprising a cylinder and piston.

4. In an air brake system the combination with a fluid pressure reservoir, a brake applying means, and means for controlling the admission of fluid pressure to said means of pneumatic means for releasing the brakes when said means is released, said means including a valve adapted to energize said releasing means when said brake applying means is deenergized.

5. In an air brake system the combination with a fluid pressure reservoir, a brake applying means, and means for controlling the admission of fluid pressure to said means of means mechanically connected to the brake mechanism for releasing the brakes when said means is opened to exhaust.

6. In a brake release system the combination with a fluid pressure reservoir, means for applying the brakes and means for controlling the application of the brakes of means mechanically connected to said brake applying means for releasing the brakes and a valve for energizing said releasing means when the brake applying means is deenergized.

7. In a brake release system the combination with a fluid pressure reservoir, means for applying the brakes and means for controlling the application of the brakes of means for releasing the brakes and a spring pressed valve for energizing said releasing means when the brake applying means is deenergized.

8. In an air brake system the combination with a fluid pressure source and brake applying means of means mechanically connected to said brake applying means for releasing the brake and means for energizing the releasing means when the brake applying means is deenergized.

In testimony whereof I have hereunto set my hand on this 29th day of July A. D., 1926.

JOHN S. McWIRTER.
